UNITED STATES PATENT OFFICE.

ALBERT JAMES WALKER, OF JACKSONVILLE, FLORIDA.

HORSESHOE.

SPECIFICATION forming part of Letters Patent No. 585,992, dated July 6, 1897.

Application filed February 29, 1896. Serial No. 581,360. (No model.)

To all whom it may concern:

Be it known that I, ALBERT JAMES WALKER, of Jacksonville, in the county of Duval and State of Florida, have invented a new and 5 Improved Horseshoe, of which the following is a full, clear, and exact description.

The object of the invention is to provide a new and improved horseshoe arranged with sufficient spring to readily yield at the toe to 10 permit expansion and contraction of the animal's hoof, so as to prevent sores and allow full development of the animal's gait.

The invention consists principally of a horseshoe having its toe provided with a 15 transverse slot into which opens a longitudinal slit extending outwardly from the slot at or near the middle of the toe.

Reference is to be had to the accompanying drawings, forming a part of this specification, 20 in which similar characters of reference indicate corresponding parts in all the figures.

Figure 1 is a perspective view of the improvement. Fig. 2 is a plan view of the same, and Fig. 3 is a sectional side elevation of the 25 same on the line 3 3 of Fig. 2.

The shoe has its toe or crown portion partly separated by a transverse slit A³, and slits A' A' extend laterally in opposite directions from the inner end of the slit A³, separating 30 the toe of the shoe into an unbroken inner bridge portion or piece A² and an outer rear portion, which latter is separated by the slit A³ to permit the yielding action of the bridge portion. The slits A' are shown nearer to 35 the inner than to the outer edge of the shoe,

and this is preferred. Now it will be seen that by this arrangement the bridge-piece A² permits the sides to give sufficiently in a lateral direction to accommodate the sides to the expansion and contraction of the hoof as 40 the animal steps on the ground or lifts his hoof.

The slit A³ is sufficiently wide to permit the outer portions of the heel to move toward or from each other, according to the expansion 45 and contraction referred to, and at the same time the heel has sufficient bearing-surface on the under side of the hoof, almost the same as in an ordinary horseshoe. The sides of the shoe are provided with the usual apertures 50 for the passage of the nails for fastening the shoe in place on the animal's hoof.

Having thus fully described my invention, I claim as new and desire to secure by Letters Patent—

A horseshoe having its toe or crown portion partly separated by a transverse slit extending from its outer toward its inner side, and having slits extending laterally from the inner end of said transverse slit in opposite 60 directions, the said transverse and lateral slits separating the toe of the shoe into an unbroken inner yielding bridge portion and an outer wear portion separated to permit the yielding action of the bridge portion, all 65 substantially as shown and described.

ALBERT JAMES WALKER.
